UNITED STATES PATENT OFFICE.

EDWARD C. SCHMELZKOPF, OF MADISON, WISCONSIN, ASSIGNOR TO GISHOLT MACHINE COMPANY, OF MADISON, WISCONSIN, A CORPORATION OF WISCONSIN.

REAMER.

Application filed November 13, 1922. Serial No. 800,771.

To all whom it may concern:

Be it known that I, EDWARD C. SCHMELZKOPF, a citizen of the United States, residing at Madison, in the county of Dane and State of Wisconsin, have invented certain new and useful Improvements in Reamers, of which the following is a specification.

This invention relates to improvements in reamers, and has reference more especially to tools of that type which are employed to finish, smooth and size a hole in various metals. It is well known that in the use of such tools, after a reamer has finished a number of holes the sharp cutting edges of the tool begin to wear, and the diameter of the hole in the work is thereby reduced a fraction of a thousandth of an inch. In order to keep the hole in the work to a standard dimension, a reamer must be quickly and accurately adjusted to its normal diameter. The main object of the present invention is to provide an improved reamer that can be adjusted or re-sized more easily and in much less time than is required for any similar reamer now known.

Another object of the invention is to provide, in a reamer of this type, a blade-clamping device that will not only allow endwise adjustment of the blade to increase or decrease the cutting diameter of the tool, but will also automatically take care of slight variations in the clamping lengths of the blades, and will also enable slight adjustments of the cutting diameter to be made, without requiring any shifting of the disc clamp at the lower end of the reamer relatively to the body of the tool. A still further object of the invention is to provide a reamer of this type in which the blades will be rigidly held in place in all adjusted positions, so that they will be practically as solid and immovable as they would be if made integral with the body.

In order that my invention may be readily understood by machinists and others skilled in the art of machine tools, I have, in the accompanying drawings, illustrated two practical embodiments of the invention which have been found to satisfactorily effectuate the stated purposes and objects thereof; and referring thereto—

Fig. 1 is a side elevation, in axial section through its upper half, of a reamer embodying my invention, and in which the blade

slots and blades are formed with parallel sides;

Fig. 2 is an end elevation of the complete tool, viewed from the right of Fig. 1;

Fig. 3 is a half section on the line 3—3 of Fig. 1.

Fig. 4 is a top plan of one of the blades;

Fig. 5 is an end elevation of the blade shown in Fig. 4 viewed from the lower end of the latter;

Figs. 6, 7 and 8 are views corresponding with Figs. 1, 2, and 3, respectively, showing a reamer wherein the blade slots and blades are tapered both longitudinally and transversely;

Fig. 9 is an inner side elevation of the blade clamp disc, which is the same in both forms of reamer shown;

Fig. 10 is a top plan of the blade shown in Figs. 6, 7 and 8;

Fig. 11 is a side elevation of the same blade as viewed from the bottom of Fig. 10; and

Fig. 12 is an end elevation of the same blade viewed from the right of Fig. 11.

In both forms of the invention shown, the reamer comprises essentially a body formed with longitudinal blade slots, blades slidably fitting said slots and formed with inclined end wall portions to secure an inward camming effect under endwise pressure by the clamping and holding devices, a blade adjusting ring threaded on the inner end of the reamer body and formed with a tapered or beveled inner side engaged with the inclined rear end walls of the blades, and a transversely elastic blade clamp disc attached to the outer end of the body preferably by screws passed therethrough and into tapped holes in the body, and formed with a circumferential flange having a beveled or tapered inner side engaged with under-cut cam surfaces on the outer end walls of the blades.

Referring first to the form of the invention illustrated in Figs. 1 to 5 inclusive, 12 designates as an entirety the reamer body, preferably made of high carbon steel heat treated. The smaller sizes are made solid with a taper shank, while the larger sizes, such as that herein shown, are made with an axial bore 13 to receive standard reamer arbors. The body 12 has a plurality (six as herein shown) of accurately milled blade

slots 14 in its circumference, these slots being parallel with the axis. The side walls of the slots are parallel throughout, and their bottom walls 15 are formed on a low 5 outward taper or incline from points near the inner end to the outer end thereof as clearly shown in Fig. 1.

The blades 16, of which one is shown in detail in Figs. 4 and 5, are formed of a uniform width to accurately fit the side walls 10 of the slots 14, and each blade has a tapered or inclined bottom wall 17 that lies in contact with the inclined bottom wall 15 of the blade slot. On its outer side each blade has 15 a cutting edge 18, herein shown as oblique, but, of course, the cutting edge may be oblique, parallel or spiral, as desired, since this detail is immaterial to the present invention. Each blade has at its inner end a 20 downwardly and rearwardly inclined end wall portion 19, and at its outer end an under-cut downwardly and forwardly inclined end wall portion 20.

The inner end of the reamer body is 25 externally threaded for some distance, as shown at 21, and mounted thereon is a blade-adjusting ring 22 having an inner beveled side 23 that fits the inclined end wall portions 19 of the blades and, when the adjusting ring 30 is screwed up, advances the blades lengthwise in their slots in an obvious and well-known manner; this adjusting ring being quite common in reamers of this type. The adjusting ring 22 may be provided with 35 a scale indicated in Fig. 1 by which the fine adjustments of the cutting diameter effected by turning up the ring may be accurately determined. Mounted on the body behind the adjusting ring 22 is an ordinary locking ring 40 24 to prevent accidental loosening of the adjusting ring 22.

To the forward end of the reamer body 45 is attached by clamp screws 25 an annular disc clamp designated as an entirety by 26. This clamp is formed with a short inwardly 50 extending peripheral flange 27 that has a beveled or tapered face 28 fitting the undercut tapered or beveled end portions 20 of the blades. The reamer body is formed with 55 tapped holes 29 in its outer end to receive the screws 25; and the disc clamp 26 is formed with countersunk holes 30 to receive the tapered heads 31 of the screws. Preferably each screw is formed with a central 60 hexagonal socket 32 in its head for the application of a wrench; but the particular formation to accommodate a screw driver is immaterial.

The disc clamp 26 is made of highly tempered steel and sufficiently thin to afford a slight transverse bending capacity in any direction. In a reamer having six blades 65 three of these clamp screws are preferably employed, one mid-way between each pair of adjacent blades, as shown in Fig. 2.

The manner in which the blades are rigidly held while working, and the manner in which the cutting diameter may be increased or decreased, will be readily apparent from the foregoing, but may be briefly 70 outlined as follows. With the disc clamp 26 in place, the adjusting ring 22 is turned up until the blades are rigidly clamped endwise by the oppositely tapered walls 23 and 28 of the adjusting ring and disc clamp respectively, which by a camming action draws each blade downwardly onto the bottom wall of the blade slot. If this does not give the exact desired cutting diameter, the latter may be increased by backing off the disc 75 clamp slightly and correspondingly turning up the adjusting ring; the reverse of these adjustments obviously effecting a decrease in the cutting diameter, the outward and inward radial movements of the blades that 80 occur simultaneously with their longitudinal movements resulting, of course, from the co-operation of the inclined bottom walls of the blades with the inclined bottom walls of the slots. If the clamp lengths, (by 85 which is meant the distance between the tapered end walls 19 and 20) of the several blades are not exactly the same, very small variations can be taken care of by further tightening of one or more of the disc clamp 90 screws 25, which thereby produces a slight inward bending of the clamping flange 27 to fit the blade or blades that are slightly under normal clamping length. Moreover, a very slight increase of cutting diameter 95 100 can be effected by the application of increased pressure at the inner ends of the blades by further turning up the adjusting ring 22 alone, the peripheral portion of the disc clamp 26 springing outwardly sufficiently to permit such fine adjustment without resetting the clamp screws 25. To effect adjustments of any substantial amount, however, the positions of both the ring 22 and the disc clamp 26 must be shifted endwise 105 110 of the reamer body.

The form of the invention illustrated in Figs. 6 to 12 inclusive embodies identically the same structural characteristics, so far as the blade-clamping devices are concerned, 115 as the form shown in Figs. 1 to 5 inclusive and already described. In this form of the invention, however, one side wall 33 of each blade slot, instead of being parallel to the opposite wall, is inclined outwardly relatively to the opposite side wall, as clearly shown in Fig. 8, thereby producing a slot of decreasing width from top to bottom, or of wedge shape. The radially inclined wall 33 is slightly inclined longitudinally relatively 120 to the opposite side wall except at its lower edge which is parallel with the lower edge of the opposite wall, so that the slot, except at its bottom is slightly wider at its rear or inner end than at its forward or outer end, 125 130

this characteristic of the slot appearing in perspective in Fig. 7. The blades 16', of which one is shown in detail in Figs. 10 to 12, of course have side walls corresponding with and adapted to fit the side walls of the blade slots; the side wall 34 thereof tapering radially and also longitudinally, except at its lower edge, so as to be parallel throughout with the correspondingly tapered side wall 33 of the slot.

By reason of the transverse or radial wedge formation of the blades and blade slots, the inward clamping action of the adjusting ring 22 and the disc clamp 26 draws the blades very tightly into the slots and clamps them in working position with great rigidity. When the cutting diameter is increased or decreased by outward or inward endwise adjustment of the blades, the radial adjustment of the latter is effected by the longitudinal taper of the co-operating side walls 33 and 34 of the blade slot and blade, rather than by any co-operation between the inclined bottom walls of the slot and blade which are out of contact. This construction has the advantage over the construction shown in Figs. 1 to 5 inclusive, of clamping the blades under a wedging fit of the blades themselves in their slots, so as to obtain even greater rigidity of the blades relatively to the body than in the first described structure. So far as the blade clamping means are concerned, however, these are identical with the construction first described.

35 I claim—

1. In a reaming tool, the combination with a body formed with longitudinal blade slots,

of blades fitting said slots and formed with beveled end walls, each of said slots and its blade having contacting walls that are inclined lengthwise relatively to the axis of the body whereby endwise adjustments of the blades are accompanied by radial adjustments thereof, a ring threaded on said body and formed with a beveled inner side fitting and embracing the rear beveled end walls of said blades, and a transversely elastic disc clamp opposite and adjustably secured to the forward end wall of said body and having an inwardly directed peripheral flange formed with a beveled side fitting and embracing the forward beveled end walls of said blades.

2. In an adjustable reamer, the combination of a body formed with longitudinal blade slots of wedge-shape both lengthwise and crosswise and narrowest at their bottoms, the longitudinal edges or the bottoms of said slots being parallel, blades of corresponding wedge-shape fitting said slots with their bottom walls out of contact with the bottom walls of the latter and formed with beveled rear end portions and oppositely beveled undercut forward end portions, an adjusting ring threaded on said body and in thrusting and clamping engagement with the rear beveled end portions of said blades, and a transversely elastic annular disc clamp opposite and adjustably attached to the forward end of said body and formed with a peripheral flange in thrusting and clamping engagement with the undercut forward beveled end portions of said blades.

EDWARD C. SCHMELZKOPF.
